Attorneys

UNITED STATES PATENT OFFICE.

JAMES R. COPLAND, OF DANVILLE, VIRGINIA, ASSIGNOR TO CROMPTON & KNOWLES LOOM WORKS, OF WORCESTER, MASSACHUSETTS, A CORPORATION OF MASSACHUSETTS.

WEFT-REPLENISHING MECHANISM.

Application filed August 25, 1922. Serial No. 584,329.

To all whom it may concern:

Be it known that I, JAMES R. COPLAND, a citizen of the United States, residing at Danville, in the county of Pittsylvania and 5 State of Virginia, have invented a new and useful Weft-Replenishing Mechanism, of which the following is a specification.

This invention relates to mechanism for replenishing the weft or filling in an automatic loom. In such looms, when using two or more kinds of colors of weft or filling, it is customary to indicate a filling change whenever a shuttle is substantially exhausted. Upon such indication, a weft carrier of the desired kind will be advanced to transfer position, from which position the weft carrier will normally be promptly transferred to the exhausted shuttle.

Failure of transfer from any cause, such 20 as failure of a shuttle to box properly, should be followed by prompt removal or release of the indicated weft carrier from transfer position, so that another weft carrier corresponding to the active shuttle may 25 be advanced to transfer position if a transfer is indicated.

Weft carrier releasing devices for such purposes have been heretofore used and a 30 patent to Lauzon, No. 1,261,563, issued April 2, 1918, shows a weft carrier release which is normally inoperative between transfers and which is moved to operative position only upon indication of transfer.

It is the object of my invention to improve the construction of the weft carrier releasing device therein shown, giving it a 35 freer swinging movement about an axis substantially removed from its point of contact with the weft carrier and permitting it to 40 move in a direction better fitted to avoid damage if a weft carrier becomes misplaced in the shuttle during transfer thereto.

With this general object in view, my invention is shown specifically in certain arrangements and combinations of parts which will be hereinafter described and more particularly pointed out in the appended claims.

A preferred form of my invention is 50 shown in the drawings in which

Fig. 1 is a left hand side elevation of a weft carrier magazine embodying my improvements;

Fig. 2 is a partial rear elevation thereof;

Fig. 3 is a detail sectional elevation, taken 55 along the line 3—3 in Fig. 1;

Fig. 4 is a detail plan view, looking in the direction of the arrow 4 in Fig. 2; and

Fig. 5 is a detail sectional view of the releasing lever.

Referring to the drawings, I have shown parts of a four color stationary weft carrier magazine of a usual type and comprising a magazine frame 10 adapted to be bolted to a loom frame, not shown. Such magazines are commonly used with looms of the drop-box type employing a corresponding number of shuttles. When weft exhaustion of a certain shuttle is indicated, a weft carrier W of the corresponding kind or color 70 is released and descends to the position shown in Fig. 1, where it engages a guide or ledge 11 on the front side and my improved weft carrier releasing lever 12 on the rear side.

The lever 12 is provided with a head 13 pivotally mounted on a stud 14 fixed in a supporting arm 15. The arm 15 is angularly adjustable upon a cross rod 16 fixed to the frame 10 and forming a permanent part of the magazine structure. A spring 17 is coiled around the rod 16, one end thereof being secured in the arm 15 and the depending free end 18 thereof engaging the lever 12 and pressing it yieldingly forward to the position shown in Fig. 1. A stop screw 12^a adjustably limits such forward movement. The release lever 12 may be adjusted vertically by swinging the arm 15 on the cross rod 16.

In order to withdraw the lever 12 to release a weft carrier, I provide a plunger 20 having its upper end pivoted to a lever 21 mounted on a rock shaft 22. The opposite end of the lever 21 is connected by a link 23 to a shuttle feeler 24. These parts are arranged to be moved by mechanism (not shown) which advances a weft carrier to transfer position. The release lever 12 is curved at its lower end and extends forward to the point at which the weft carriers are held pending transfer. This curved shape of the lever 12 is clearly shown in dotted lines in Fig. 1. The plunger 20 has an offset or angularly disposed lower end portion as clearly shown in Fig. 3 which engages the curved lower portion of the release lever 12.

In the normal position of the parts, the shuttle feeler 24 is raised and the plunger 20 is depressed. When thus depressed, the offset lower end of the plunger has a cam action with the curved lower portion of the lever 12, forcing the same rearwardly and releasing any weft carrier which may have been held in transfer position. Upon indication of transfer, the shuttle feeler 24 is depressed and the plunger 20 is raised, releasing the lever 12 and permitting it to swing yieldingly forward to engage and support the weft carrier which is presented for transfer. After transfer, the parts return to their first or normal position and the weft carrier is released if for any reason the transfer has not been completed.

The lever 12 is preferably provided with a ledge 25 along one or both edges to engage the wire rings on the weft carrier head and thus assist in guiding the weft carrier during transfer.

The operative connections for the rock shaft 22 are not shown herein and form no part of my invention, but for a full disclosure and description thereof reference is made to the prior patents to Ryon, No. 972,722, issued October 11, 1910, and No. 1,022,108, issued April 2, 1912.

It will be noted that the stud 14 which forms a pivot for the release lever 12 is mounted in the upper portion of the magazine and at a point relatively remote from the point of contact of the release lever with the weft carrier. The pivot is also located a relatively short distance to the rear of the point of contact so that the movement of the lower end of the lever is in an arc which is nearly horizontal, instead of in an arc which is substantially vertical, as in the prior patent to Lauzon. This permits a much smoother and easier release movement of the lever and also permits the lever to swing easily backward when engaged by a misplaced weft carrier caught in the shuttle.

The lever 12 is preferably made of mild steel, which permits the shape of the lever to be changed somewhat to suit varying conditions. This is in addition to adjustment by the screw 12^a.

Having thus described my invention and

the advantages thereof, it will be evident that changes and modifications can be made therein by those skilled in the art within the spirit and scope of my invention as set forth in the claims, and I do not wish to be otherwise limited to the details herein disclosed, but what I claim is:—

1. In a loom, a stationary weft carrier magazine having a plurality of vertical compartments, a weft carrier release lever formed as a single unit and mounted to swing about a pivot in the upper part of said magazine remote from its point of contact with the weft carrier, means to advance said lever yieldingly to operative position, and means to withdraw and hold said lever in normal inoperative position between indications of transfer, said lever having swinging movements of different extent about a single center to release a weft carrier and also to clear a misplaced weft carrier.

2. In a loom, a stationary weft carrier magazine having a plurality of vertical compartments, a weft carrier release lever formed as a single unit and mounted to swing about a pivot in the upper part of said magazine remote from its point of contact with the weft carrier, an arm on which said lever is pivoted, a cross rod fixed in said magazine on which said arm is mounted for angular adjustment to raise and lower said lever, and means to secure said arm in a selected angular position.

3. In a loom, a stationary weft carrier magazine having a plurality of vertical compartments, a weft carrier release lever formed as a single unit and mounted to swing about a pivot in the upper part of said magazine remote from its point of contact with the weft carrier, and means to withdraw said lever from operative position, said lever having a curved lower portion and said means including a plunger engaging said curved lower portion and having a cam action therewith to withdraw said lever.

In testimony whereof I have hereunto affixed my signature.

JAMES R. COPLAND.
